UNITED STATES PATENT OFFICE.

EDWARD M. MYERS, OF NEW YORK, N. Y.

TOY.

997,407.

Specification of Letters Patent. Patented July 11, 1911.

Application filed October 17, 1910. Serial No. 587,371.

To all whom it may concern:

Be it known that I, EDWARD M. MYERS, a citizen of the United States, residing at New York, in the county of New York and 5 State of New York, have invented certain new and useful Improvements in Toys, of which the following is a full, clear, and exact description; such as will enable others skilled in the art to which it appertains to 10 make and use the same.

This invention relates to toys, and more particularly to a device adapted to be used by roller skaters.

One of the objects of the present invention is to provide a device of the above character that will act as a partial support for the skater and be simple to construct and cheap to manufacture.

Another object is to provide such a device that will be light but safe and substantial in its construction.

Other objects will be in part obvious and in part pointed out hereinafter.

The invention accordingly consists in the 25 features of construction, combinations of elements and arrangement of parts which will be exemplified in the construction hereinafter set forth, and the scope of the application of which will be indicated in the 30 following claims.

In the accompanying drawing, wherein is shown one of various possible embodiments of this invention, Figure 1 is a side elevation showing the manner in which the device may be used; and Fig. 2 is a plan view of the same.

Similar reference characters refer to similar parts throughout the different views of the drawing.

Referring to the drawing in detail, 1 denotes a pole member provided near one end thereof with a block 2 on which are positioned laterally extending anti-friction roller means 3. These rollers, which extend slightly to each side of the pole or stick, provide the required stability and prevent tipping of the device when in use. This end of the pole is preferably provided with a slightly pointed metallic ferrule 4 whereby the same may be stuck into the ground or pavement to assist the user when going up hill, the device being used as a pole or staff. Intermediate the ends of this pole, near the middle thereof, is provided a 55 bracket 5 which is clamped to the pole by means of a set screw 6 or the like. This

bracket 5 is adapted to support a seat 7 which is movably secured thereto as by means of a set screw hinge 8 whereby the angular relation between the seat and the pole may be regulated according as the device is used by a small or large child. A spring member 9 may be interposed between this hinge connection and the seat, if so desired. The purpose of these adjusting 65 mechanisms will be apparent when one considers that as the seat is moved up and down along the pole member 1 to accommodate children of different sizes, the angular relation between the seat and the pole should 70 be changed as the angle formed between the pole and the ground changes when the device is in use. Near the opposite end of the pole member 1 is positioned a second adjustable bracket or clamp 10 having clamping means 11 adapted to carry a handle 12 which extends at each side of the pole member 1, as clearly shown in Fig. 2.

It is thought that the manner of operating and using this device will be apparent from 80 the above description and the accompanying drawing, but will nevertheless be set forth in brief as follows: A child, for instance, provided with roller skates straddles the pole member 1, grasps the handle 12 and 85 partially supports himself upon the seat 7, as clearly shown in Fig. 1. When in this position he will easily roll down the slightest incline, or may be pushed by another person along a level space, as occasion requires. 90 If it is desired to adjust the mechanism for a larger or smaller child, the seat may be moved up or down along the pole member by loosening the set screw 6, and the angle between the seat and the pole may be 95 changed by means of the set screw on the hinge 8. The position of the handle may be changed by loosening the set screw 11 and moving the bracket along the pole as desired.

It is thus seen that this invention accomplishes among others all of the objects and purposes above set forth in a practical and simple manner; and it will also be seen that the device will be simple in construction and cheap to manufacture, and may be safely used by children of varying ages, affording them constant pleasure.

As many changes could be made in the above construction and many apparently widely different embodiments of this invention could be made without departing from

the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope 10 of the invention, which, as a matter of language, might be said to fall therebetween.

Having described my invention, what I claim as new and desire to secure by Letters Patent is:

15 1. In a device of the character described, in combination, a pole member of sufficient strength to support a rider, a seat supported on said pole member intermediate its ends, said seat being angularly adjustable, a handle attached to said pole member, said seat and said handle being adjustable along the 20 length of said pole member, and roller means positioned at one end of said pole

member adapted to support the weight thereof.

2. In a device of the character described, in combination, a pole, a block near one end of said pole, antifriction roller means mounted on said block at each side of said pole in position to engage the ground, an 25 adjustable member mounted near the middle of said pole, a spring-supported seat hinged to said member, means whereby said member may be adjusted along said pole, a bracket near the opposite end of said pole, 30 a handle mounted on said bracket, and means whereby said bracket may be adjusted along said pole, said pole having a pointed metallic ferrule at the end adjacent said roller means.

In testimony whereof I affix my signature, in the presence of two witnesses.

EDWARD M. MYERS.

Witnesses:

S. H. WATSON,
P. A. BLAIR.
